DESIGN FOR A DRESS

Herbert M. Harris, New York, N. Y.

Application March 23, 1940, Serial No. 91,180

Term of patent 3½ years

To all whom it may concern:

Be it known that I, Herbert M. Harris, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific double collared dress disclosed, of the specific front seams having visible stitching extending from the sleeve to the waistline, the upper and inner seams on each side presenting a yoke like appearance as shown.

I claim:

The ornamental design for a dress, substantially as shown and described.

HERBERT M. HARRIS.
